UNITED STATES PATENT OFFICE.

ERNEST G. OFELDT, OF NYACK, NEW YORK.

WATER-REGULATOR.

1,232,377.

Specification of Letters Patent.

Patented July 3, 1917.

Application filed September 30, 1916. Serial No. 123,075.

To all whom it may concern:

Be it known that I, ERNEST G. OFELDT, a citizen of the United States, and a resident of Nyack, in the county of Rockland and State of New York, have invented certain new and useful Improvements in Water-Regulators; and I do hereby declare the following to be a full, clear, and exact description of the invention, such as will enable others skilled in the art to which it appertains to make and use the same.

This invention relates to improvements in water regulators, and more particularly to the valve structure,—one object of the invention being to so construct a valve structure for water regulators that the same will operate to keep its seat clean, and so that the accurate seating of the valve shall be insured without depending upon true alignment of some other movable part or fixed guiding means.

With this and other objects in view, the invention consists in certain novel features of construction and combinations of parts as hereinafter set forth and pointed out in the claim.

In the accompanying drawings, Figure 1 is a sectional view of a water regulator embodying my improvements, and Fig. 2 is a detail view of the valve.

1 represents a casing provided with suitable parts for connection with a boiler, and with an inlet opening 2, the wall of the latter being threaded for the accommodation of a nipple 3. This nipple is made with an intermediate collar 4 and with threaded end portions 5 and 6,—the threaded portion 6 being adapted to receive a suitable water supply connection (not shown) and the threaded portion 5 passing through the opening 2 of the casing. The free end of the portion 5 of the nipple forms a seat 7 for a valve 8. This valve comprises a disk 9, from the center of which a conical portion

10 depends so that it may enter the bore of 45 the nipple and become seated on the seat 7.

The valve 8 is not secured to any part of the regulator but is free to be rotated and oscillated by the action of the flowing water, so that it will thus operate to keep the 50 seat 7 clean at all times and insure the perfect and accurate seating of said valve.

The flat face of the valve rests freely against the flat face of a weight 11 carried by one end of a lever 12. This lever is pivotally supported at 13 and the weight 11 (which is intended to counterbalance a ball float 14 at the other end of the lever) may consist of a box filled with heavy material, such as lead and the pivotal mounting of the 60 lever may be located at one end of this box or weight.

It is apparent that the lever 12 will be caused to oscillate by the changing level of the water within the casing and in consequence of these movements of the lever, the valve will be opened and closed.

Having fully described my invention what I claim as new and desire to secure by Letters-Patent, is:—

In a water regulator, the combination with a casing, a nipple entering the same and having a valve seat at its inner end and a float lever pivotally mounted in said casing and having a weight at one end, of a 75 freely movable valve comprising a disk resting freely against the under face of said weight and a conical portion to enter the nipple and to engage the seat at the inner end thereof.

In testimony whereof, I have signed this specification in the presence of two subscribing witnesses.

ERNEST G. OFELDT.
